SAFETY RAZOR

George Taylor, Hollinghurst, Kingsway, Pen-
wortham, Preston, EnglandApplication June 11, 1932, Serial No. 616,713
In Great Britain September 22, 1931

12 Claims. (Cl. 30—12)

This invention relates to a safety razor provided with the known device of a face roller, which when applied to the face causes a reciprocation of a carrier for the blade.

- 5 Heretofore, in such safety razors the blade carrier has been mounted to slide on a plurality of longitudinal bars or a plurality of feet have been provided on the carrier at each end, the feet sliding in grooves in the razor frame.
- 10 The object of the present invention is to improve on the known reciprocating razor by providing a single axial support for the carrier and setting guides which position the carrier so as to guide the operative edge of the blade in set position with respect to the face roller. In such a construction friction is reduced to a minimum as the support and the guides require only a small superficial area, accuracy of setting is ensured and maintained even when wear occurs and adjustment of the setting may be effected, and the whole razor rendered more simple, compact and easier to construct than hitherto. A further object is to construct such a razor so that its detachable parts shall be readily dismantled for 25 changing the blade.

The accompanying drawing shows the invention applied to a razor employing a wafer blade which is adapted to be bent into curved form when mounted on the razor.

- 30 Referring to the accompanying drawing:—
Figure 1 is a side elevation showing the complete razor with handle,
Figure 2 is a plan of Figure 1 with the blade and backing plate removed,

35 Figure 3 is an enlarged view of about double the full size upon the line A—A of Figure 1,

Figure 4 is a detailed view showing the blade set and guided by the end plates, and

40 Figure 5 illustrates a double edged blade of the usual character.

Figure 6 is a detail end view with parts omitted, of a modification wherein the single pivot for the carrier is of rectangular cross-section.

In carrying out the invention according to the 45 forms illustrated in the drawing a double edged blade, for example as shown in Figure 5, is attached to a carrier 1 by means of the curved backing plate 2, provided, as usual, with steady pins adapted to enter the holes 3 of the carrier 1 and 50 attached thereto by means of the hollow screw 4 threaded to the projecting stem 5 attached to the backing plate 2.

The carrier 1 is supported by a single axial support at the center constituted by pivot rods 55 20, 21, adapted to slide respectively in end frames

14 and 15 about which rods the carrier is adapted to tilt. On the carrier is provided a pin 6 working in the groove 7 of the face roller 8 and the carrier is shaped as regards its top face 9 so that as the backing plate 2 is drawn downwards by the action of the screw 4 the blade 10 is pulled down hard upon the edges of the surface 9 and bent to the form shown in Figure 3, whereby its operating edge 11 is brought by the action of the setting guide lugs 12 into a correct setting with 60 regard to the roller 8 so as to give the necessary 65 shaving angle.

It will be seen that the guide for the carrier and the blade is achieved by means of the upstanding lugs 12, 13 forming part of the end frames 14, 15. 70 By means of the reduced surface provided by these lugs 12, 13 very accurate setting of the blade may be achieved so that it only rests lightly thereon during reciprocation, and moreover a relatively small friction surface is presented to the 75 blade during its movement. An adjustment of the set of the blade is provided by these lugs in as much that they may be filed to bring the operating edge 11 nearer to the face roller 8. In place of the lugs upon or adjoining the end frames 80 14, 15, the upper periphery of each frame may be so shaped that the edges of the blade rest lightly thereon, as shown in Figure 4, in which case no upstanding lugs are needed. It will be seen that 85 the shape of an end plate, for example 14, is such that when resting on the surface as regards the edges of the blade the central portion thereof is preferably free from the said surfaces for the purpose of reducing friction.

16 is a roller provided along the inoperative 90 edge of the razor as a safety guard therefor.

To control and limit the tilt of the carrier 1 when the blade is removed upstanding pins, such as 17, 18, are provided, attached to the cross plate 19 so that the pin 6 has a slight play in the groove 7 but cannot come out of engagement therewith. When the blade is mounted on the carrier the pins do not engage therewith so that the carrier 1 can be moved with very little friction and guided by the contacting surfaces of the 95 blade 10 with the setting guides on the end frames.

In place of the pins 17 and 18, to limit the tilt of the carriage 1 the pivot of the carrier may be constituted by rods 20a of rectangular cross section as shown in Figure 6 instead of circular, and projecting one from each end of the carrier as in the preceding figures, the holes in the end plates being also of rectangular cross section but slightly larger than the rods 20a so as to permit a slight 105 tilt when the blade is removed.

110

By providing a tilting carrier in association with the setting guides, the blade is permitted to take up automatically its correct setting when being mounted on the carrier, and moreover adjustment of the setting can also be effected as above described, the whole construction being extremely flexible, simple and accurate.

In a modification the pins 17 and 18 may engage the carrier and the setting guides on the 10 end plates may be omitted. To permit of access to and manipulation of the central screw 4, the end frames 14 and 15 are connected to a handle 22 by means of a bridge piece 23 which embraces the central screw 4 as shown, the handle preferably being a separate integer which is screwed into the bridge piece.

The invention provides an effective means of achieving the desired result of a razor blade which reciprocates while in contact with the face at the 20 same time that it is carefully guided so that no harm can come to the user and the shaving is thus facilitated and improved in effect.

In place of the roller 14 a sharpening surface for the inoperative edge of the blade 10 may be 25 arranged; this construction is the subject of my co-pending application for a patent No. 616,714.

What I claim is:—

1. A safety razor for a double edged blade, comprising in combination a razor frame including 30 end plates, a reciprocating blade carrier, a central pivotal support comprising pivot rods one projecting from each end of the carrier into the said end plates, upstanding pins secured to the said frame beneath the carrier to limit the rocking movement of the latter, a rotatable face roller mounted between the end plates adjacent one side of the carrier, means for reciprocating the carrier by rotation of the face roller, means for fixing the blade to the carrier with one edge adjacent the face roller, and guiding means on the said end plates determining the angle of set of the said edge with respect to the face roller, whilst presenting the minimum friction surface to the reciprocation of the blade.

2. A safety razor for a double edged blade comprising in combination a razor frame including end plates, a reciprocating blade carrier, a central pivotal support comprising pivot rods one projecting from each end of the carrier into the 55 said end plates, limit means determining the rocking movement of the carrier, a rotatable face roller mounted between the end plates adjacent one side of the carrier, means for reciprocating the carrier by rotation of the face roller, means for fixing the blade to the carrier with one edge adjacent the face roller, guide faces on the said end plates shaped at their ends to engage the edges of the blade to determine the set of the said edge with respect to the face roller and further shaped at the centre to clear the central zone of the blade, whereby a minimum friction surface is presented to the reciprocation of the blade.

3. A safety razor for a double edged blade comprising in combination a razor frame including end plates, a reciprocating blade carrier, a central pivotal support comprising pivot rods one projecting from each end of the carrier into the said end plates, limit means determining the rocking movement of the carrier, a rotatable face roller mounted between the end plates adjacent one side of the carrier, means for reciprocating the carrier by rotation of the face roller, means for fixing the blade to the carrier with one edge adjacent the face roller upstanding abutments on each end plate mounted on each side of the

carrier and adapted to engage the blade and determine the set of the said edge with respect to the face roller whilst presenting a minimum friction surface to the reciprocation of the blade.

4. In a safety razor, the combination with a frame including a face roller, of a reciprocating blade carrier operated by the face roller, including a pivotal support slidably mounted in the frame so that the carrier may tilt about the pivot and setting guides controlling the tilt of the carrier so as to guide the operative edge of the blade in set position with respect to the face roller.

5. In a safety razor the combination with a frame including a face roller, of upstanding end plates on the frame, with a space between them, a blade carrier operated by the face roller to reciprocate in the said space and having a pivotal central support in each end plate, and setting surfaces on each end plate directly engaging the end of the blade immediately adjoining same so as to guide the operative edge of the blade in set position with respect to the face roller.

6. In a safety razor, the combination with a frame including a face roller, of a reciprocating blade carrier operated by the face roller, including a central pivotal support slidably mounted in the frame so that the carrier may tilt about the pivot, and setting guides on the frame 105 on each side of the pivot, said guides engaging the blade so as to guide the operative edge of the blade in set position with respect to the face roller.

7. In a safety razor the combination with a frame including a face roller, of a reciprocating blade carrier operated by the face roller, including a central pivotal support slidably mounted in the frame so that the carrier may tilt about the pivot, abutments between the frame and the 115 carrier for limiting the tilt of the carrier when the blade is removed therefrom, and setting guides on the frame on each side of the pivot, said guides engaging the blade so as to guide the operative edge of the blade in set position with regard to the face roller.

8. In a safety razor the combination with a frame including a face roller, of a reciprocating blade carrier operated by the face roller, including a central pivotal support slidably mounted in the 125 frame so that the carrier may tilt about the pivot, limit pins positioned on the frame on each side of the pivot and the carrier so as to limit the tilt of the carrier when the blade is removed, and setting guides on the frame on each 130 side of the pivot, said guides engaging the blade so as to guide the operative edge of the blade in set position with regard to the face roller.

9. In a safety razor, the combination with a frame including end plates and a face roller 135 mounted in the end plates, of a reciprocating blade carrier operated by the face roller, including a central pivotal support slidably mounted in the end plates so that the carrier may tilt about the pivot, and setting guides on the end 140 plates, said guides engaging the blade so as to guide the operative edge of the blade in set position with respect to the face roller.

10. In a safety razor the combination with a frame including end plates and a face roller 145 mounted in the end plates of a reciprocating blade carrier operated by the face roller including a central pivotal support slidably mounted in the end plates so that the carrier may tilt about the pivot, setting means on the end plates on each 150

side of the pivot to guide the operative edge of the blade with respect to the face roller, a cross plate connecting the end plates, and abutments between the cross plate and the carrier so as to limit the tilt of the carrier when the blade is removed.

11. In a safety razor, the combination with a frame including end plates and a face roller mounted between the end plates, of a reciprocating carrier operated by the face roller, including a central pivotal support of rectangular cross section slidably engaging in recesses in the end plates so as to permit the carrier a slight tilt and setting guides on the frame on each side of the pivot, said guides engaging the blade so as to guide the operative edge of the blade in set position with respect to the face roller.

12. In a safety razor the combination with a frame including end plates and a face roller mounted in the end plates of a reciprocating blade carrier operated by the face roller including a central pivotal support slidably mounted in the end plates so that the carrier may tilt about the pivot, setting means on the end plates on each side of the pivot to guide the operative edge of the blade with respect to the face roller, a backing plate including a screwed projecting stem passing through the carrier for fixing the blade thereto, a handle, a bridge piece connecting the end plates and the handle, and an internally operating securing nut for the stem embraced by the bridge piece so as to permit access to and manipulation of the nut.
